Primary Examiner — David G Muller*Assistant Examiner* — Christina Gabrielle Cosden(74) *Attorney, Agent, or Firm* — Justin Lampel(57) **CLAIM**

The ornamental design for removable truck tailgate locking device, as shown and described.

DESCRIPTION

FIG. 1 is a perspective view of a removable truck tailgate locking device showing the claimed design;

FIG. 2 is a side view thereof;

FIG. 3 is a side view thereof;

FIG. 4 is a front view thereof;

FIG. 5 is a back view thereof;

FIG. 6 is a top view thereof;

FIG. 7 is a bottom view thereof; and,

FIG. 8 is a view of the device in the unlocked orientation. The broken lines illustrate portions of the removable truck tailgate locking device that form no part of the claimed design.
